WILLIAM PICKENS AND PETER DALRYMPLE, OF CHICAGO, ILLINOIS.

Letters Patent No. 102,968, dated May 10, 1870.

IMPROVEMENT IN MACHINES FOR DRESSING MILLSTONES.

The Schedule referred to in these Letters Patent and making part of the same.

To all whom it may concern:

Be it known that we, WILLIAM PICKENS and PETER DALRYMPLE, of Chicago, in the county of Cook and State of Illinois, have invented a Machine for Dressing Millstones; and we do hereby declare that the following is a full, clear, and exact description thereof, which will enable those skilled in the art to make and use the same, reference being had to the accompanying drawings and letters marked thereon making a part of this specification, in which—

Figure 1 is a perspective representation of our invention.

Figure 2, a vertical sectional elevation of the same, looking in the direction indicated by dart x.

Figure 3, an elevation of a part appertaining thereto, detached from the other parts.

The nature of the present invention consists of a substantial frame, which rests upon the face of a millstone, and centers upon the top of the spindle of the bed-stone or in the bale of the runner, and which is provided with an automatic feed-arm, which is operated upon by a screw-rod, and spaces the distance which the cracks or grooves in the stones are to have from each other as the whole, together with the details of the machine, is hereinafter fully specified.

I A B represents a substantial semicircular frame, which is made of cast-iron, and of such size as to have a suitable bearing on a millstone.

To the central part of this frame, and near the straight part I, is attached a hub, C, which supports an adjustable centre piece or pivot, D, the lower end of which has a step formed in it, to bear on the top of the spindle when a bed-stone is being dressed, and which is to be inverted so that its top end may bear in the step of the bale of the runner when the latter is being dressed; a set-screw, E, being tapped into said hub, holds the pivot D in place when adjusted.

That part of the frame shown at I is provided with a guide-track, P P, in order that a head-block, O, may readily move back and forth thereon. This head-block O supports and carries an arm, G, which is also provided with a track, S S, in order that the gauge-head R may be readily moved back and forth on said arm when the cracks in the stone are being made.

In order to give the arm G an automatic feed motion which will so move the diamond-point a on the stone as to make the cracks the proper distance from each other, I use the following devices: A screw-rod, J, is placed in front of that part of the frame shown at I, and has bearings in each of its ends h; and on

the two ends of this rod are securely fastened ratchet-wheels l, which are turned by means of pawls m, fig. 1. These pawls are pivoted to arms U, which are pivoted to the circular part A of the frame, and support a rod, H, which is operated as follows: a connecting-rod, L, is jointed to said rod H, and to a vertical lever, M, which is pivoted to the arm G, at N. The lower end of lever M is pivoted to a horizontal bar, Y, which has a projecting pin, T, figs. 1 and 2, against which the gauge-head R strikes when making a crack, and carries said bar toward the end of arm G, and consequently so turns the lever M on its pivot N as to cause the connecting-rod L to move the arms U. By means of this movement, the pawls m turn the ratchet-wheels l one notch, and turn the screw-rod J in a nut, K, fig. 2, fastened to block-head O, and consequently moves forward the arm G attached to said head, the distance which the arm moves being governed by the pitch of thread on the screw-rod J. It is well, however, here to state that the arm G should move about one-twenty-fifth of an inch at each cut of the diamond-point a, this being the distance that the cracks in the stone are usually made apart.

In order to fill the space between the ends of that part of the frame I and the ratchets l, and to prevent the arms U from moving back too far, looped arms, V, are pivoted to the said arms U, and their looped parts pass around the ends of the screw-rod J, the slots in the loop being just long enough to allow the arms U to move the required distance.

When it is required to remove the gauge-head from the guides S S, the pin T, on the rod Y, can be raised up into a notch, d, fig. 2, made in the arm G.

Having thus described our invention, what we claim, and desire to secure by Letters Patent, is—

1. The arm G, provided with a traversing head-block O, track S S, gauge-head R, and point a, combined with the screw-rod J, operated by the ratchets l, pawls m, arms U, rod H, connecting-rod L Y, and lever M.

2. The adjustable and reversible center D, combined with the frame I A B, hub C, and arm G of a stone-dressing machine.

WILLIAM PICKENS.
PETER DALRYMPLE.
